US00D928728S

(12) **United States Design Patent** (10) **Patent No.:** **US D928,728 S**
(45) **Date of Patent:** **** Aug. 24, 2021**

(54) **REMOTE CONTROL**

(71) Applicant: **Hunter Douglas Inc.**, Pearl River, NY (US)

(72) Inventors: **Fred Bould**, Menlo Park, CA (US); **Anson Cheung**, San Francisco, CA (US); **Joshua Cope-Summerfield**, San Francisco, CA (US); **Scott Stephenson**, Westminster, CO (US); **Kevin Dann**, Englewood, CO (US); **Jesse Perreault**, Denver, CO (US)

(73) Assignee: **Hunter Douglas Inc.**, Pearl River, NY (US)

(**) Term: **15 Years**

(21) Appl. No.: **29/718,125**

(22) Filed: **Dec. 20, 2019**

(51) LOC (13) Cl. **14-03**

(52) U.S. Cl.

USPC **D13/168**

(57) **CLAIM**

The ornamental design for a remote control, as shown and described.

DESCRIPTION

FIG. 1 is a perspective view of a remote control according to a first embodiment of the claimed design;

FIG. 2 is a front view of the remote control of FIG. 1;

FIG. 3 is a rear view of the remote control of FIG. 1;

FIG. 4 is a right side view of the remote control of FIG. 1;

FIG. 5 is a left side view of the remote control of FIG. 1;

FIG. 6 is a top view of the remote control of FIG. 1;

FIG. 7 is a bottom side view of the remote control of FIG. 1;

FIG. 8 is a perspective view of a remote control according to a second embodiment of the claimed design;

FIG. 9 is a front view of the remote control of FIG. 8;

FIG. 10 is a rear view of the remote control of FIG. 8;

FIG. 11 is a right side view of the remote control of FIG. 8;

FIG. 12 is a left side view of the remote control of FIG. 8;

FIG. 13 is a top side view of the remote control of FIG. 8;

FIG. 14 is a bottom view of the remote control of FIG. 8;

FIG. 15 is a perspective view of a remote control according to a third embodiment of the claimed design;

FIG. 16 is a front view of the remote control of FIG. 15;

FIG. 17 is a rear view of the remote control of FIG. 15;

FIG. 18 is a right side view of the remote control of FIG. 15;

FIG. 19 is a left side view of the remote control of FIG. 15;

FIG. 20 is a top side view of the remote control of FIG. 15; and,

FIG. 21 is a bottom view of the remote control of FIG. 15.

The dash-dash broken lines illustrate environmental structure and form no part of the claimed design.

The dash-dot-dash broken lines define a boundary of the claimed design and are not an ornamental part of the design itself.

1 Claim, 18 Drawing Sheets
